(57) **CLAIM**

The ornamental design for a three-layer tilted head earplugs, as shown and described.

DESCRIPTION

FIG. 1 is a front, right side, top perspective view of a three-layer tilted head earplugs showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged, detailed view of the region denoted by the reference number 8 in FIG. 1.

The broken lines depict portions of the three-layer tilted head earplugs that form no part of the claimed design.

The cord is shown with a symbolic break in its length. The appearance of any portion of the article between the break lines forms no part of the claimed design.
